(57) **CLAIM**

I claim, the ornamental design for the decorative jewelry for cell phone, as shown and described.

DESCRIPTION

FIG. 1 is a front elevational view of the decorative jewelry for a cell phone showing my new design;

FIG. 2 is a left side elevational view thereof;

FIG. 3 is a top plan view thereof;

FIG. 4 is a bottom plan view thereof; and,

FIG. 5 is a perspective view thereof.

The broken lines shown in the drawings represent environmental subject matter and form no part of the claimed design.
